METHOD AND APPARATUS FOR SUPPLYING
CURRENT TO EXCITER LAMPSGeorge Friedl, Jr., Fanwood, N. J., assignor to
International Projector Corporation, New York,
N. Y., a corporation of Delaware

Application March 16, 1940, Serial No. 324,317

19 Claims. (Cl. 179—100.3)

The present invention relates generally to a method and apparatus for supplying and controlling current for light sources, and more particularly, to a method and apparatus for supplying and controlling current for exciter lamps, such as those employed in sound reproduction systems.

In modern motion picture theatres, two projecting machines are usually employed, one machine being "on" while the other machine is "off." Exciter lamps employed in such machines are usually supplied with smooth direct current so that there are no fluctuations in the current passing through the exciter lamps to affect the sound emitted by the sound reproducing equipment. Since the usual source of current supply is alternating current, such current is usually rectified and filtered before being supplied to the exciter lamps. Rectifying equipment for this purpose is comparatively expensive and, therefore, in order to avoid the cost of duplicate rectifying equipment, as well as the additional operating and maintenance expenses entailed thereby, the present invention provided for a single rectifying unit which only supplies rectified current for the lamp in the "on" machine while unrectified current is supplied to the lamp on the "off" machine. When, however, a theatre is equipped with only one rectifying unit for the exciter lamps, sound outages resulting from the breakdown thereof may occur. To prevent such outages the present invention provides means for operating the exciter lamp of the "on" machine as well as the "off" machine on alternating current during such emergency.

Another feature of the present invention is the provision of means for heating an exciter lamp with alternating current preliminary to its operation. The preheating current supplied is less than the usual operating current and such preheating serves to prevent the shock resulting to a cold lamp when a full operating load is applied thereto.

Still another feature of the present invention is the provision of means in a sound reproducing device not in use for preheating one exciter lamp with alternating current at a temperature reduced from its normal operating value while operating the exciter lamp in the sound reproducing device in use at its normal operating value with direct current.

A further feature of the present invention is the provision of means for rapidly increasing the preheating current from the reduced value to a value equal to the operating current.

An additional feature of the present invention is the provision of means for rapidly switching the type and value of current supplied to the various exciter lamps.

Other features and advantages will become apparent from the following description and the drawings in connection therewith in which,

Fig. 1 is a schematic diagram of current supply equipment embodying the present invention.

Fig. 2 is a continuation of Fig. 1 and is a schematic diagram of the switching circuit employed in connecting the equipment illustrated in Fig. 1 to two exciter lamps.

Referring now to Fig. 1 the current from one side of a source of alternating current supply, such as a power line 10, is connected through a circuit breaking switch 11 and a suitable fuse 12 to one arm 13 of a double pole double throw switch 14. One of the associated poles 15 of the switch 14 is in turn connected to one end of the primary 16 of a transformer 17 forming a part of a full-wave rectifier. The other end of the primary 16 is connected directly to the other side of the source of alternating current supply 10. Taps for regulating voltage output may be provided on the primary. The secondary of transformer 17 includes two small coils 18 and 19 which supply current for heating the filaments of rectifying tubes 20 and 21, respectively. Said rectifying tubes may be of the type known commercially as "Tungar" tubes. The main coil 22 of the secondary has a center tap 23 and a number of end taps 30. The center tap 23 may be connected through choke coils 24 and 25, and through ballast lamp 26, test strap 27 and rheostat 28 to pole 29 of the double pole double throw switch 14. When the movable arms of the double pole double throw switch 14 in contact with the poles 29 and 15, pole 29 is connected to the output terminal 31 through the arm 32 of switch 14.

Movable arms 33 and 34 are arranged adjacent the ends of the coil 22 to make contact with a selected one of the taps 30 adjacent thereto. The movable arm 33 is connected to the filament in rectifying tube 21 and movable arm 34 is in turn connected to the filament of rectifying tube 20. The plates of the two rectifying tubes are connected together and to an output terminal 35.

Suitable condensers 36 and 37 are arranged in the filter circuit, condenser 36 being connected at one end thereof to the plates of the rectifying tubes and at the other end to a point in between choke coils 24 and 25, and condenser

37 being connected on one side thereof to the plate of the rectifying tubes and on the other side thereof to pole 28 of the double pole double throw switch 14. Rheostat 38 is connected between the plates of the rectifier tubes and the terminal of the strap 27 adjacent the ballast lamp 26.

The foregoing equipment completes the rectifier circuit. The transformer 17 supplies alternating current of proper voltage. The coils 18 and 19 of the secondary serve to furnish current for the filaments of the rectifying tubes 20 and 21, the main coil 22 supplying the current which is rectified, the current being rectified through the rectifying tubes 20 and 21 and smoothed out by the filter circuit including choke coils 24 and 25, and condensers 36 and 37. The rheostat 28 serves to control the amount of direct current supply and also cooperates with rheostat 38 in maintaining on ballast lamp 26 the voltage and current value at which the ballast lamp is designed to operate. The taps on the primary and secondary of transformer 17 may be adjusted so that the movable arms on rheostats 28 and 38 are usually at their center positions thus providing a range on both sides of the center positions for subsequent adjustments. The test strap 27 is designed to be removed from the circuit for inserting an ammeter therein to measure the direct current output.

For supplying alternating operating current and alternating current of a value less than operating current for preheating purposes, the step-down transformer 39 is provided. One side of the primary of transformer 39 is connected directly to one side of the source of alternating current 18, the other side of the primary 39 being connected to the other side of the alternating current supply 18 through a suitable fuse 40 and switch 41. It will be seen that when switch 41 is open no current will be supplied either to the rectifying circuit or to the alternating current supply circuits. Taps may be provided on the primary of transformer 39 for adjusting the voltage on the secondary.

The secondary of transformer 39 is tapped intermediate its ends, this tap 41 being so located on the secondary that the difference of potential between tap 41 and one end 42 of the secondary is less than the difference of potential being between tap 41 and the end 43. For instance, the difference of potential between tap 41 and end 42 may be two volts while the difference between tap 41 and end 43 may be 9½ volts. The lower potential may be used when preheating an exciter lamp while the higher potential may be used when operating said lamp at full brilliance. End 42 is connected to an output terminal 44. Tap 41 is connected to output terminal 35 and end 43 is connected through a rheostat 45 to the terminal 36 of the double pole double throw switch 14. It will be seen that when the double pole double throw switch is in its upper position as illustrated in Fig. 1 so that switch arm 32 contacts pole 46 that the end 43 of the secondary coil of transformer 39 will be connected to output terminal 31. The rheostat 45 regulates the alternating operating current delivered at output terminals 31 and 35.

While I have illustrated and described transformer 39 as being a single transformer having a tapped secondary, it will be understood by those skilled in the art that two transformers may be substituted as equivalent thereto, one of said transformers having its secondary connected in

the same position as 41 and 42 and the other of said transformers having its secondary connected in the same position as 41 and 43.

From the foregoing it will be apparent that when the double pole double throw switch 14 is in its lower position as viewed in Fig. 1 alternating current will be supplied to the rectifying circuit and the rectifying circuit will in turn supply direct current at output terminals 35 and 31. On the other hand, when the movable arms of the double pole double throw switch 14 are in their upper position the alternating current supplied to the rectifying circuit will be cut off and the rectifying circuit disconnected from output terminal 31, while in place thereof, alternating current for operating the exciter lamp will be supplied at output terminals 35 and 44. Furthermore, it will be evident that, whatever the position of the movable arms of the double pole double throw switch 14, preheating alternating current, of less value than the operating current, will be constantly supplied at output terminals 35 and 44. It will, therefore, be seen that operating current either direct or alternating is supplied at terminals 35 and 31 and preheating current is supplied at terminals 35 and 44. Thus terminal 35 is common to both the preheating and operating current supplies.

In the present specification and in the appended claims the phrase "operating current" when used in relation to current supplied to a light source or an exciter lamp signifies current of a value sufficient to cause said light source or exciter lamp to light with full brilliance, this being the usual condition of such light source or exciter lamp when the sound reproducing apparatus in which it is employed is functioning to reproduce sound.

In Fig. 2 is illustrated a switching arrangement for supplying the current derived from the output of the apparatus illustrated in Fig. 1 to two exciter lamps, the preheating current being supplied to one lamp, and the operating current to the other lamp, said switching arrangement being adapted to reverse the supply of current to the lamps.

As is stated hereinbefore, output terminal 35 is common to both the preheating and the operating current supplies. The output terminal 35 is connected to one terminal 47 of exciter lamp 48 and to one terminal 49 of exciter lamp 50. The output terminal 31 for supplying operating current is connected to one pole 51 of a double pole double throw switch 52, the output terminal 44 for supplying preheating current being connected to the adjacent pole 53 of said switch. Pole 53 is connected with its diagonally opposite pole 54 and pole 51 is connected with its diagonally opposite pole 55. It will be seen that when switch 52 is thrown to the left as viewed in Fig. 2 the upper movable arm 56 of switch 52 will be connected to output terminal 44. In the same position of the switch the lower arm 57 will be connected to output terminal 31. When the switch is moved to the right as viewed in the same figure the connections will be reversed, arm 56 being connected to output terminal 31 and arm 57 being connected to output terminal 44. Arms 56 and 57 may be connected to the movable arms of a switch 58, the poles of which are connected together in the same fashion as the poles of switch 52. One pole 59 is connected to the terminal 60 of exciter lamp 48 and the adjacent pole 61 is connected to the terminal 62 of exciter lamp 50.

It will be seen that with both switch arms in the left hand position as viewed in Fig. 2, operating current will be supplied to exciter lamp 50 and preheating current will be supplied to lamp 48. It will also be apparent that by moving the 5 movable arms of either switch into an opposite position the current supplied to the lamps 48 and 50 will be reversed.

While I have described two switches 52 and 58 as being arranged in the circuit it will readily be understood that one switch may be dispensed with and the switching operation controlled solely by the other. However, for the purpose of controlling the current supply from different points the arrangement of two or more switches in the circuit is desirable. As many switches as are desired can be inserted in the suggested manner into the switching circuit, each switch acting to interchange the current supplied to the lamps without operating any other switch. Furthermore, switches 52 and 58 may be mechanically interlocked with switches 48 and 52 described in a co-pending application bearing Serial No. 324,280, filed March 16, 1940, entitled "Method and apparatus for electronic change-over," Fowler Durst, inventor, so that by a single manual operation a change may be effected not only from an exciter lamp in one machine to an exciter lamp in another machine but also from a sound reproducing apparatus in the first machine to the sound reproducing apparatus in the other. When such switches are also mechanically interlocked with dowser controls, a quick changeover can readily be effected from one projecting machine to another.

Where there are three machines each having its own exciter lamp another switching arrangement may be employed for supplying current thereto. This arrangement is illustrated in Fig. 3.

As stated hereinbefore, current for "operating" an exciter lamp is obtained at terminal 31 and common terminal 35. Current for preheating an exciter lamp is obtained at terminal 44 and the common terminal 35. Terminals 44 and 31 are connected to a series of double pole double throw reversing switches 63, 64 and 65. The connection of these switches to terminals 44 and 31 are the same as those hereinbefore described in relation to switches 52 and 58 with the exception that there is one extra reversing switch. The common terminal 35 is connected to one side of each of the exciter lamps 66, 67, and 68.

The arms 69 and 70 of reversing switch 65 are connected to arms 71 and 72, respectively, of a selector switch 73. Arms 71 and 72 are each associated with three poles, said arms being mechanically interlocked although not electrically connected together. The selector switch 73 may be a "Yaxley" switch such as that described in Patent No. 1,975,247. Poles 74, 75 and 76 associated with arm 71 are connected to exciter lamps 66, 67, and 68, respectively. Poles 77, 78, and 79 associated with arms 72 are also connected to these lamps, but in the following order: pole 77 to lamp 68, pole 78 to lamp 66, pole 79 to lamp 67.

It will be seen that with all the switches in the position illustrated in Fig. 3 "operating" current will be supplied to lamp 66 and preheating current to lamp 67. Lamp 68 will not have any current supplied to it. It will be immediately apparent that by switching one of the reversing switches 63, 64 or 65 that the current supplied to lamps 66 and 67 will be interchanged with

current for preheating purposes being supplied to lamps 68 and current for operating purposes being supplied to lamp 67.

When the selector switch 73 is moved so that arm 71 is in contact with pole 74 and arm 72 is in contact with pole 77, lamps 66 and 68 will be connected to the current supply while lamp 67 will be disconnected. Preheating current will be supplied to one of the lamps 66 or 68 and "operating" current will be supplied to the other of said lamps. By operating one of the reversing switches the current to these two lamps may be interchanged.

When selector switch 73 is moved so that arms 71 and 72 are in contact with poles 76 and 79, respectively, lamps 68 and 67 are connected to the current supply and lamp 66 is disconnected therefrom. Preheating current is supplied to one of said lamps and "operating" current is supplied to the other lamp, operation of any of the reversing switches interchanging the current supply.

It will thus be seen that by operating the selector switch 73 any two of the three lamps may be connected to the current supply and thereafter the current supplied to either of the two selected lamps may be interchanged by operation of any one of the reversing switches 63, 64 or 65. From the foregoing description it will be apparent that the switch arrangement illustrated in Fig. 3 may be extended to control and supply current for more than three exciter lamps.

Where it is desired that the exciter lamp on the "off" machine be adjusted, preliminary to switching said machine to "on" operation, it is necessary to bring said lamp to a state of full brilliance by supplying sufficient current therefor. To accomplish this I prefer to interpose a single pole double throw switch 80 in the connection between terminal 44 and end 42 of the secondary of transformer 39. Arm 81 of switch 80 may be connected to terminal 44. Pole 82 of switch 80 may be connected to end 42 of the secondary of transformer 39. Ordinarily arm 81 is in contact with pole 82 and the current supplied at terminals 44 and 35 is only sufficient to heat an exciter lamp preliminary to its operation. When, however, it is desired that the exciter lamp connected with terminals 44 and 35 be adjusted preliminary to regular operation in an "on" machine, arm 81 is arranged to make contact with pole 83. Pole 83 is connected to end 43 of the secondary of transformer 39 and at end 43 and the center tap 41 current of full "operating" value is obtained. It will be noted that pole 83 is connected directly to end 43, thereby avoiding the drop in potential across resistor 45.

From the foregoing description it will also be apparent that I have provided current supplying equipment for use with an alternating current supply source, which equipment is adapted to supply direct operating current for one exciter lamp and alternating current for heating another lamp preliminary to its operation and, furthermore, that I have provided means for interchanging the current supplied to the respective lamps.

It will also be seen that I have provided current supplying equipment for operation on an alternating current supply source designed to supply direct current for operation of exciter lamps and also designed to substantially immediately supply alternating current for operating exciter lamps. With said alternating current operating supply I have also provided alternating current

supply for heating an exciter lamp preliminary to its operation as well as for interchanging the supply of current to the various lamps.

It is also to be understood that while I have described transformer 39 as supplying alternating current of "operating" value for emergencies, such current may be employed for regular as well as emergency operation with exciter lamps of sufficient thermal lag.

While a preferred embodiment of my invention has been described, it is to be understood that this description is not a limitation upon the scope of the invention, which is to be determined only by the appended claims.

I claim:

1. In combination, an alternating current power supply line, a plurality of light sources, a rectifier having its input connected to the power supply line, said rectifier being adapted to supply direct current for operating a light source, a transformer having its primary connected to said power supply line and having a first part of its secondary adapted to supply alternating current for operating a first of said light sources, and having a second part of its secondary adapted to supply alternating current for heating a second of said light sources preliminary to operation, the second part of the secondary being connected to the second light source, the output of the rectifier being connected to the first light source and means for substantially simultaneously disconnecting the input of the rectifier from the power supply line and connecting the first part of the secondary of the transformer to the first light source.

2. In combination, an alternating current power supply line, a plurality of light sources, a rectifier having its input connected to the power supply line, said rectifier being adapted to supply direct current for operating a light source, a transformer having its primary connected to said power supply line and having a first part of its secondary adapted to supply alternating current for operating a light source, and having a second part of its secondary adapted to supply alternating current for heating a light source preliminary to operation, the second part of the secondary being connected to a first light source, the output of the rectifier being connected to a second light source and switching means for disconnecting the input of the rectifier from the power supply line and connecting the first part of the secondary of the transformer to the first light source after disconnecting the second part of the transformer secondary therefrom.

3. In combination, an alternating current power supply line, a plurality of light sources, a rectifier having its input connected to the power supply line, said rectifier being adapted to supply direct current for operating a light source, a transformer having its primary connected to said power supply line and having one part of its secondary adapted to supply alternating current for operating a light source, and having a second part of its secondary adapted to supply alternating current for heating a light source preliminary to operation, the second part of the secondary being connected to a first source, the output of the rectifier being connected to a second light source and means for substantially simultaneously disconnecting the output of the rectifier from the second light source and connecting the first part of the transformer secondary to the second light source.

4. In combination, an alternating current

power supply line, a plurality of light sources, a rectifier having its input connected to the power supply line, said rectifier being adapted to supply direct current for operating a light source, a transformer having its primary connected to said power supply line and having one part of its secondary adapted to supply alternating current for operating a light source, and having a second part of its secondary adapted to supply

10 alternating current for heating a light source preliminary to operation, the second part of the secondary being connected to a first light source, the output of the rectifier being connected to a second light source and switching means for disconnecting the output of the rectifier from the second light source and connecting the first part of the transformer secondary to the first light source after disconnecting the second part of the transformer secondary therefrom.

5. In combination, an alternating current power supply line, a rectifier, a transformer, the input of the rectifier and transformer being connected to the power supply line, a plurality of light sources, the output of the rectifier being connected to one of said light sources, the output of the transformer being connected to a second of said light sources and means for disconnecting the output of the rectifier from the first-mentioned light source and connecting the output of the transformer to said first-mentioned light source.

6. In combination, an alternating current power supply line, a rectifier, a transformer, the input of the rectifier and transformer being connected to the power supply line, a plurality of light sources, the output of the rectifier being connected to one of said light sources, the output of the transformer being connected to a second of said light sources and means for disconnecting the output of the transformer from the second-mentioned light source and connecting the output of the rectifier to said second-mentioned light source.

7. In combination an alternating current power supply line, a rectifier, a transformer, the input of the rectifier and transformer being connected to the power supply line, a plurality of light sources, an electrical circuit connecting the output of the rectifier to a first light source and the output of the transformer to a second light source, means arranged in the circuit for switching the output of the rectifier to the second light source and the output of the transformer to the first light source.

8. In combination an electric power supply line, a rectifier, a transformer, the input of the rectifier and transformer being connected to the power supply line, a plurality of light sources, one light source connected to the output of the rectifier, another light source connected to the output of the transformer and switching means for interchanging the connections of the output of the rectifier and the output of the transformer to the light sources.

9. The method of operating a pair of light sources which comprises supplying alternating current of operating value to one light source while heating the second light source preliminary to its operation with alternating current of less than the operating value, and substantially simultaneously switching the alternating current supply of operating value to the second light source and shifting the alternating current supply of less than the operating value to the first mentioned light source.

10. In combination an electric power supply line, a rectifier, a transformer, the rectifier and transformer being connected to the power supply line, a plurality of light sources, one light source connected to the output of the rectifier, another light source connected to the output of the transformer, said rectifier being adapted to supply direct current for operating a light source, said transformer being adapted to supply alternating current for heating a light source preliminary to operation, and switching means for interchanging the connections of the output of the rectifier and the output of the transformer to the light sources.

11. In combination an alternating current power supply line, a rectifier, a transformer, the input of the rectifier and transformer being connected to the power supply line, a plurality of light sources, the output of the rectifier being connected to one of said light sources, the output of the transformer being connected to a second of said light sources, said rectifier being adapted to supply direct current for operating a light source, said transformer being adapted to supply alternating current for heating a light source preliminary to operation, and means for disconnecting the output of the rectifier from the first-mentioned light source and connecting the output of the transformer to said first-mentioned light source.

12. In combination an alternating current power supply line, a plurality of light sources, a rectifier, the input of the rectifier connected to the power supply line, said rectifier adapted to supply direct current for operating a light source, a transformer having its primary connected to the power supply line and having a tapped secondary adapted to supply, at the tap and one end of the secondary, alternating current for operating a light source, and adapted to supply, at the tap and the second end of the secondary, alternating current for heating a light source preliminary to operation, the tap and the second end of the secondary being connected to a first light source, the output of the rectifier being connected to a second light source and means for substantially simultaneously disconnecting the output of the rectifier from the second light source and connecting the secondary of the transformer at the tap and the first end thereof to the second light source.

13. The method of operating a pair of light sources which comprises supplying direct current to one light source while heating the other light source preliminary to its operation with alternating current of less than the operating value required by said lamp.

14. The method of operating a pair of light sources which comprises supplying direct current to one light source while heating the other light source preliminary to its operation with alternating current of less than the operating value required by said lamp and upon the shutting off of the direct current to the first light source supplying alternating current of the proper operating value to the first light source.

15. In combination, an alternating current supply line, a plurality of light sources, a transformer having its primary connected to the current supply line and having a tapped secondary, the sec-

ondary being adapted to supply alternating current for operating a light source at the tap and one end of the secondary, and adapted to supply alternating current for heating a light source preliminary to its operation at the tap and the second end of the secondary, the secondary being connected at the tap and the first end thereof to one light source and connected at the tap and the second end thereof to a second light source and means for interchanging the current supply to each of said light sources.

16. In combination, an alternating current supply line, a plurality of light sources, a transformer having its primary connected to the current supply line and having a tapped secondary, the secondary being adapted to supply at two of its terminals alternating current for operating a light source, said terminals being connected to one light source, said secondary also being adapted to supply at two of its terminals alternating current for heating a light source preliminary to its operation, said last-mentioned terminals being connected to a second light source and means for interchanging the current supply connected to said light sources.

17. In combination, an alternating current supply line, a plurality of light sources and a transformer having its primary connected to the current supply line and having a tapped secondary, the secondary being adapted to supply at two of its terminals alternating current for operating a light source, said terminals being connected to one light source, said secondary also being adapted to supply at two of its terminals alternating current for heating a light source preliminary to its operation, said last-mentioned terminals being connected to a second light source.

18. In combination, an alternating current supply line, a plurality of light sources, a transformer having its primary connected to the current supply line and having a tapped secondary, the secondary being adapted to supply at two of its terminals alternating current of a value sufficient to illuminate said light sources to full brilliance, said secondary also being adapted to supply at two of its terminals alternating current of a lesser value for heating a light source preliminary to its normal operation, said last-mentioned terminals being connected to a light source and switching means for connecting said light source to the first-mentioned pair of terminals.

19. In combination, an alternating current supply line, a plurality of light sources, a transformer having its primary connected to the current supply line and having a tapped secondary, the secondary being adapted to supply at two of its terminals alternating current for operating a light source, said terminals being connected to one light source, said secondary also being adapted to supply at two of its terminals alternating current for heating a light source preliminary to its operation, said last-mentioned terminals being connected to a second light source and means for substantially simultaneously disconnecting one of said pairs of terminals from the light source to which it has been connected and connecting it to a third light source.

GEORGE FRIEDL, JR.
